*Primary Examiner—Prabhakar G. Deshmukh
Attorney, Agent, or Firm—Mark C. Jacobs, Esq.***[57] CLAIM**

The ornamental design for a two part vehicle transmission shipping container, as shown and described.

DESCRIPTION

FIG. 1 is a top perspective view of a two part vehicle transmission shipping container showing my new design; FIG. 2 is a top perspective view of the upper portion thereof; FIG. 3 is a bottom perspective view of the upper portion thereof;

FIG. 4 is a bottom perspective view of the lower portion thereof;

FIG. 5 is a top perspective view of the lower portion thereof; and,

FIG. 6 is a bottom plan view of the upper portion of the first embodiment.

The upper and lower portions of the design are shown separately in FIGS. 2-6 for clarity of illustration.
